UNITED STATES PATENT OFFICE.

JOHN W. THOMAS, JR., OF NASHVILLE, TENNESSEE.

RAILWAY SWITCH AND SIGNAL MECHANISM.

SPECIFICATION forming part of Letters Patent No. 606,602, dated June 28, 1898.

Application filed April 21, 1898. Serial No. 678,374. (No model.)

To all whom it may concern:

Be it known that I, JOHN W. THOMAS, Jr., of Nashville, Tennessee, have invented certain new and useful Improvements in Railway Switch and Signal Mechanism, of which the following is a specification.

My invention relates to railway switch and signal interlocking machines, and more particularly to that type of such machines in which "preliminary locking" is employed. By "preliminary locking" I mean that the interlocking of the levers of the machine is effected, not by the movement of the switch or signal lever itself, but by the movement of the latch-lever with which each of such levers is provided and which must be first manipulated in order to release and permit the movement of the switch or signal lever to which it is applied. In such a machine a link or rocker is used to transmit movement from the latch to the tappets, flops, or locking-bars, the interlocking between the levers of the machine being accomplished by means of said tappets, flops, or locking-bars in conjunction with dogs of suitable form and construction, as well understood by those skilled in the art to which this invention relates.

It is the main object of my invention to handle a double-plunger lock for facing-point switches from a mechanical interlocking machine by means of preliminary locking, or, in other words, by means of the latch instead of the switch or signal lever itself. This has been done in the case of a single-plunger lock; but I am not aware of any preliminary-locking mechanical interlocking machine by which a double-plunger facing-point lock has been handled or which, in fact, is constructed and adapted to do this work. So far as I am aware double-plunger facing-point locks, when employed at all, have been used in conjunction with mechanical interlocking machines which have no preliminary locking—as, for example, the interlocking machine which is the subject of my Patent No. 468,160 of February 2, 1892. The link or rocker which I employ in this connection is also adapted for use in connection with a "two-position" signal-operating lever or with slight modification can be adapted for service in connection with a "three-position" signal-operating lever.

I shall first describe my improvements by

reference to the drawings accompanying and forming part of this specification, and will then point out in more particularity in the 55 claims those features which I believe to be new and of my own invention.

In the said drawings, Figure 1 is a plan of a portion of a railway-track in which the switch-points are combined with a double-plunger lock in accordance with my invention. Fig. 2 is a sectional side elevation of the interlocking machine-lever in the "tower" or "cabin" for operating said facing-point lock. Fig. 2^a is a view of the link block or pin detached. Fig. 3 is a plan on enlarged scale of the double-plunger facing-point lock in one of its locking positions. Fig. 4 is a longitudinal central section of the same. Fig. 5 is a similar section representing the side shifted, 70 so as to bring it to the intermedial position, in which the switch-points are unlocked. Fig. 6 is a cross-section of the device on line 6 6, Fig. 3. Fig. 7 is an enlarged elevation of the link or rocker forming part of the mechanism shown in Fig. 2. Fig. 8 is a like view of a slightly-modified form of said link.

A, Fig. 1, is a railway-track.

A' is the facing-point switch, which through the usual connections indicated in part at a 80 b c is connected to the appropriate switch-lever of the interlocking machine in the tower.

To the switch-points is connected the notched bar B, which extends through and can slide back and forth in a guide d in the base or bottom casting D of the lock. This base or casting is secured in proper position alongside of the track and is provided with suitable guides, in which is supported the slide-bar C. This slide-bar C at one end 1 90 is connected through suitable intermediaries with the point-lock-operating lever E, Fig. 2, of the interlocking machine in the tower, and its opposite end 2 may be connected, as shown in Fig. 1, to the usual detector-bar 3. Upon 95 the under side of the slide-bar C are secured two locking-lugs e f, which are so located that they are on opposite sides of the notched bar B and in the plane of notches e' f' in said bar. When the switch is thrown to one extreme of its movement, the notch e' will be brought opposite to and in register with the lug e, so that it may be entered by the latter, as shown in Figs. 3 and 4. When the switch

is thrown to the opposite extreme, the notch f' and the lug f will be brought into register. At each extreme of the movement of the slide-bar C one or the other of the lugs e or f will engage its appropriate notch e' or f' and then lock the notched bar B, and consequently the switches. When the slide-bar is in intermediate position, as in Fig. 5, both lugs e and f will be out of engagement with the notched bar and the latter, and consequently the switch will be free to move.

The facing-point switch-lock-operating lever E of the interlocking machine represented in Fig. 2 is connected to the slide-bar C at 1 by intermediaries which are well known, and therefore require no description or illustration here. The latch-lever with which said lock-operating lever is provided is shown at F. Motion from the latch-lever is transmitted 15 to the tappet j of the interlocking mechanism by means of latch-rod g , link block or pin h , (shown separately in side elevation in Fig. 2^a,) slotted link or rocker G, and connection i. The latch-rod g is provided with a lateral 20 projection g' , which constitutes the latch proper and is intended to engage one of the notches k' k^2 k^3 in the quadrant II. A spring s presses the latch-rod g and latch g' in a direction to cause the latter to engage the quadrant. The latch-lever F lifts the rod g against 25 the stress of spring s.

The link G is pivoted at m to the frame of the machine and can rock upon that pivot as a center. It is provided with a longitudinal 30 slightly-curved slot n . The headed link block or pin h extends through and can move back and forth in and lengthwise of the slot in the link and is attached to the lower end of the latch-rod g by a central bolt h' . The link 35 itself has in the lower edge of its slot and at a point about midway between the two ends of the same a gain or recess p . This feature is found in both forms of links, Figs. 7 and 8. The link in Fig. 8 has in addition to the intermediate recess p a recess p' at one end and 40 an offset or ridge p^2 p^3 at or very near the other end, the purpose of which will be hereinafter described.

The quadrant II has three notches, as shown. 45 When the lock-lever is at one extreme of its movement—viz., that shown in Fig. 2, which may be considered its normal position—the latch g' engages the notch k' , and the slide-bar C is in a position in which its lug e will engage the notch e' of the notched bar B. The switch is thus locked in position. In order to shift the switch, the lever E is moved from the position shown in Fig. 2 to its intermediate or central position, in which position 50 the latch g' will engage the central notch k^2 in the quadrant. The effect of the movement of the lever E to this position is to shift the slide-bar C to the intermediate position shown in Fig. 5, in which position both of its lugs e and f are out of engagement with the notched bar B, and the switch consequently is unlocked. The switch then by its appropriate

lever is shifted, which movement brings the notch f' of the notched bar B opposite to and in the path of movement of the lug f on the slide-bar C. Then the lock-lever E is swung over to complete its stroke and to bring its latch g' into engagement with notch k^3 in the quadrant, and this movement of the lever will cause the slide-bar to move in a direction to bring its lug f into engagement with the notch f' of the notched bar B, thus locking the switch in its shifted position.

The machine shown in Fig. 2 is supposed to be supplied with a link G, such as shown in Fig. 7. The link obtains one-half of its movement by the unlatching of the lever E before it begins its stroke and by the latching of said lever at the opposite extreme of its stroke. For instance, before the lever E can be moved from the position in which it is shown in Fig. 2 it must be unlatched. This is effected by pressing the latch-lever F toward the lever E. In so moving the latch-lever raises the latch-rod g and the latter through the link-block h tilts the link one-half of its stroke. This movement of the link-block causes the tappet j to move the appropriate distance to lock up everything in the machine except the switch-lever to which the lock-lever pertains. The lock-lever E is then swung over or reversed part way until it comes over the notch k^2 in the quadrant without imparting further movement to the link. When in this position, the recess p in the bottom edge of the slot in the link will be a straight line passing through the center or pivots m of the link and the lever E, respectively. When the latch g' reaches the center notch k^2 of the quadrant, the link-block will be opposite and just over the recess p , and the latch g' is then permitted to drop into engagement with said center notch, the link-block h dropping into the center recess p and holding the link steady in its half-way position. The lock-lever is also held firmly at half-stroke and cannot be disturbed accidentally during the operation of the switch-lever, which is reversed while the lock-lever is at rest at half-stroke. After the switch-lever has been reversed the lock-lever E is again taken hold of and fully reversed, its link-block h being lifted out of the recess p by the same movement of the latch-lever and rod which disengages the latch g' from the central quadrant-notch k^2 . During this movement of the lock-lever the link-block traverses the slot in the link without actuating the latter, but after the lock-lever is fully reversed then the descent of the latch into engagement with the quadrant-notch k^3 , occasioned by the spring s, will cause the link-block h to complete its stroke. In this concluding half-stroke of the link and the tappet j , to which it is connected, the tappet will maintain locked all conflicting levers, but will release those which control, for example, the signals which govern the right of way over the switch just reversed. The same sequence of operation takes place when the lever is thrown over

from reversed to normal position. In this way I am enabled to successfully handle and control a double-plunger facing-point switch-lock from a mechanical interlocking machine 5 with preliminary locking. The link shown in Figs. 2 and 7, while designed specially to be used with a lever handling the double-plunger facing-point lock in the manner hereinbefore described, can also be used without 10 change in connection with a two-position signal-lever.

To adapt the link for use in connection with a three-position signal-lever, the offsets or cam-ridges $p^2 p^3$ and the recess p' should be 15 added, the cam-ridges being located at the end of the slot which is occupied by the link-block h when the lever is in normal position and the recess p' in the lower edge of the slot being at the opposite or "reverse" end 20 of the slot.

The cam-ridges or offsets $p^2 p^3$ are provided, because it is necessary, with a three-position signal that the link should make its full stroke at the outset of the movement from 25 "normal" to "reverse." The raising of the link-block, due to the lifting of the latch-rod at the time the lever is being unlatched, will impart half of the stroke to the link and the other half is imparted to it by the link-block 30 at the outset of the movement of the lever, being brought into contact with and traveling over the upper cam-ridge or offset p^2 . During the remainder of the stroke of the lever the link-block traverses the slot in the 35 link without imparting movement to the latter. The recess p' is provided, so that when the lever is fully reversed its latch can drop into the reverse-quadrant notch k^2 without imparting further movement to the link, the 40 link-block at this time dropping down into the recess p' . If caution-signal is to be given, the lever is stopped at the central notch k^2 ; but if a safety-signal is to be given the lever is

fully reversed. The cam-ridge or offset p^3 is the one which operates to give one-half 45 stroke to the link when the lever is being returned from reverse to normal position. It will be noted that the lever must be brought very near to its normal position before the link is operated at all. The result, as I find 50 from actual practice, is that the signal is set or returned to "danger" before the link is moved, and consequently before the tappet is operated to return to "normal." In this way I am enabled to handle three-position 55 signals with one lever and at the same time get the proper movement of the tappet.

Having described my improvements and the best way now known to me of carrying the same into effect, what I claim herein as 60 new, and desire to secure by Letters Patent, is as follows:

1. The combination with a double-plunger facing-point switch-lock, and the lever and connections for operating the same, of the 65 latch-lever carried by said lock-lever, the latch, latch-rod and link-block, the quadrant, the tappet, and the pivoted slotted link, connected to the tappet, and engaging the link-block and provided in the lower edge of its 70 slot with an intermediate recess located as described to accomodate the link-block, when the latch is dropped into the intermediate notch of the quadrant, substantially as and for the purposes hereinbefore set forth. 75

2. The slotted link or rocker, provided with the offsets or cam-ridges $p^2 p^3$, and the intermediate recess p , and the end recess p' , substantially as and for the purposes hereinbefore set forth. 80

In testimony whereof I have hereunto set my hand this 16th day of April, 1898.

JOHN W. THOMAS, JR.
